(57) **CLAIM**

We claim the ornamental design for a protective coupler for electrical extension cords, as shown and described.

DESCRIPTION

FIG. 1 is a perspective view of the protective coupler for electrical extension cords embodying the design of the present invention.

FIG. 2 is a front elevational view thereof;

FIG. 3 is a rear elevational view thereof;

FIG. 4 is a side elevational view thereof;

FIG. 5 is a top plan view thereof; and,

FIG. 6 is a bottom plan view thereof.

The broken line showing of environment is for illustrative purposes only and forms no part of the claimed design.
